UNITED STATES PATENT OFFICE.

JOHN KELLY, OF CHICAGO, ILLINOIS.

DESIGN FOR A SHOWER-BATH RING.

SPECIFICATION forming part of Design No. 30,185, dated February 14, 1899.

Application filed January 3, 1899, Serial No. 701,053. Term of patent 14 years.

To all whom it may concern:

Be it known that I, JOHN KELLY, a citizen of the United States, residing at Chicago, in the county of Cook and State of Illinois, have 5 invented and produced a new and original Design for a Shower-Bath Ring, of which the following is a specification.

The accompanying drawing shows my design of shower - bath ring by a perspective 10 view.

As shown in the accompanying drawing, the leading or material feature of my design consists in the two arc-shaped perforated sections R of the ring A, extending in the same 15 plane from a head B, so as to describe a true circle when the sections are brought together

at their free ends. The head has ear-like bosses P on its opposite sides, from which the sections R project, and from the head extends the neck-like nipple O, shown as inclining downward in a forward direction. The ring has regular perforations.

Having described my invention, what I claim as new, and desire to secure by Letters 20 Patent, is—

The design for a shower-bath ring, as herein shown and described.

JOHN KELLY.

In presence of—

M. J. FROST,
R. T. SPENCER.
